UNITED STATES PATENT OFFICE.

JOHN M. MARTY, OF CLEVELAND, OHIO.

PANIC-BOLT.

1,079,603.

Specification of Letters Patent.

Patented Nov. 25, 1913.

Application filed June 24, 1913. Serial No. 775,490.

To all whom it may concern:

Be it known that I, JOHN M. MARTY, a citizen of the United States, residing at Cleveland, in the county of Cuyahoga and State of Ohio, have invented certain new and useful Improvements in Panic-Bolts, of which the following is a specification.

My invention relates to improvements in panic bolts or locking mechanism for emergency exit-doors, the primary object of the invention being to provide a generally improved emergency fire or panic exit bolt, the present embodiment being particularly designed and adapted for use as a panic bolt in securing the doors of school and other buildings in accordance with the laws now in force in this respect.

In accordance with the above, the invention has for its object the provision of a panic door bolt or locking mechanism which may be readily and expeditiously operated from the inside only to quickly release the door, and when so released, will be automatically latched in its released or unlocked position until the latching mechanism is released and the door bolts returned to their locked position by the janitor or other authorized attendant.

With the above-mentioned and other ends in view, the invention consists in the novel construction, arrangement, and combination of parts, hereinafter described, illustrated in one of its embodiments in the accompanying drawings, and particularly pointed out in the appended claims.

Referring to the drawings, forming a part of this specification, Figure 1, is a view of the improved panic bolt in its locked position as applied to the inner side of one of the doors, such as are commonly employed in school buildings where one of the doors is locked and only used in an emergency and the other is used continuously. Fig. 2, a perspective view of the improved locking mechanism in unlocked or released position, the latching mechanism holding the parts in such unlocked or released position.

Similar numerals of reference designate like parts throughout all the figures of the drawings.

The improved bolt operating mechanism or fastening device for emergency exit-doors comprises upper and lower lock rods or bars 1 and 2, respectively, pivotally connected at their inner or adjacent ends to a latch or bolt

operating member 3, the latter being pivotally mounted on an attaching bracket 4, said attaching bracket, in the present instance, being provided with oppositely arranged bearing lugs 4^a, between which the latch or bolt operating member 3, is pivoted through the medium of a bearing pin or member 3^a, extending through the bearing lugs 4^a.

As a means for normally holding the locked rods or bolts 1 and 2, and the attached bolt operating member 3, in their locked position, a weight 5, may be mounted upon the lower lock bolt or bar 2, and as a means for adjusting the bolts to conform to doors of varying heights, as well as providing means for automatically latching the locking mechanism or bolts in door released position, a second lock rod or bolt 1^a, is provided, the rods or bolts 1^a, and 2, being adapted to be slidably mounted in suitable guide or keeper straps (not shown) and operating in a well-known and understood manner. The lock rod or bolt 1^a, is adjustably connected to the rod or bar 1, through the medium of a clamping member 6, said clamping member 6, in the present instance, comprising two parts connected by clamping screws 6^a, said clamping member being secured, in the present instance, to the upper bar 1, by means of a bearing pin 6^b.

As a means for slidably securing or guiding the adjacent ends of the rods or bolts 1, and 1^a, in proper position, an attaching guide bracket 7, is provided, said guide bracket 7, being provided with a bearing 90 opening 7^a, to slidably receive and contain the lower end of the rod or bolt 1^a, and a guide slot 7^b, to receive and contain the upper pivoted end of the rod or bolt 1, the latching device, in the present instance, comprising a 95 spring latch member 8, secured to the side of the clamping member 6, by means of one of the screws 6^a, and depending therefrom, the lower end of said spring latch member being provided on its inner side with a latch 100 head 8^a, and adapted to bear against one side of the attaching or guide bracket 7, so that when the parts of the locking mechanism are moved to their unlocked or door releasing position, as shown in Fig. 2, of the drawings, said latch head will automatically snap into engagement with the lower portion of the attaching bracket 7, as shown in Fig. 2, and the parts will thus be held in released position as against the action of the weight 110

5, until the latch member 8, is manually released to permit the parts to return to their normal or locking position.

From the foregoing description, taken in 5 connection with the accompanying drawings, the operation and advantages of my invention will be readily understood.

Having thus described one of the embodiments of my invention, what I claim and 10 desire to secure by Letters Patent is—

1. In a panic bolt, a pivotally mounted bolt operating member provided with oppositely extending lock bars, an upper lock bar adjustably connected to one of said bars, 15 a guide bracket for the adjustably connected ends of said bars, and a latching device adapted to automatically engage with said guide bracket when said bars are moved to door released position.
2. In a panic bolt, a lock rod, a clamping member secured thereto, a lock rod adjustably mounted in said clamping member, an attaching guide bracket for said lock rods, and a spring latch carried by said clamping 25 member and bearing against one side of said attaching guide bracket whereby said spring latch is adapted to engage said attaching guide bracket when said rods are moved to door released position.
3. In a panic bolt, a lock rod, a two-part clamping member detachably connected thereto, a lock rod adjustably secured in said clamping member, an attaching guide bracket provided with a bearing opening 35 slidably receiving and containing said adjustably mounted lock rod, and a latch mem-

ber carried by said clamping member and adapted to automatically engage with said attaching guide bracket when said lock rods are moved to door released position.

4. In a panic bolt, the combination with 40 a pair of lock rods, and means for moving the latter toward and from each other; of a third lock rod adjustably connected to one of said lock rods, an attaching guide bracket 45 for the latter and the adjacent end of said adjustably connected third lock rod, and a spring latch member carried by said adjustably connected lock rod and adapted to automatically engage with said attaching 50 guide bracket when said lock rods are moved to door released position.

5. A panic bolt, comprising an attaching bracket, a bolt operating member pivotally mounted thereon, a weighted lock rod 55 depending from said bolt operating member, a second lock rod pivotally connected to said bolt operating member, a clamping member connected to said second lock rod, a third lock rod adjustably secured in said clamping 60 member, an attaching guide bracket for slidably connecting the adjacent ends of said second and third lock rods, and a spring latch member for automatically locking the parts when moved to door released position. 65

In testimony whereof I have affixed my signature in presence of two witnesses.

JOHN M. MARTY.
